[57] CLAIM

The ornamental design for a kitchen faucet handle, as shown and described.

DESCRIPTION

FIG. 1 is a perspective view of a kitchen faucet handle showing my new design;

FIG. 2 is a right side elevational view thereof, the left side being a mirror image of the right side shown;

FIG. 3 is a plan view thereof taken on plane 3—3 of FIG. 2;

FIG. 4 is a rear elevational view thereof;

FIG. 5 is a front elevational view thereof;

FIG. 6 is a bottom plan view thereof; and

FIG. 7 is a fragmentary cross-sectional view taken on line 7—7 of FIG. 2.

The broken line representation of a kitchen faucet in FIG. 1 is for purposes of illustration only and forms no part of the claimed design.
